UNITED STATES PATENT OFFICE.

JAMES W. LOVERIDGE, OF JERSEY CITY, NEW JERSEY.

HOT-AIR FEEDER FOR FURNACES.

SPECIFICATION forming part of Letters Patent No. 319,828, dated June 9, 1885.

Application filed October 28, 1884. (No model.)

To all whom it may concern:

Be it known that I, JAS. W. LOVERIDGE, of Jersey City, in the county of Hudson and State of New Jersey, have invented certain new and useful Improvements in Hot-Air Feeders for Furnaces; and I do hereby declare that the following is a full, clear, and exact description thereof, reference being had to the accompanying drawings, in which—
10 Figure 1 shows a view in front elevation of my hot-air-feeding pipe as situated on the front upper edge of the bridge-wall; Fig. 2, a plan view of the same, the walls of the furnace being broken away; Fig. 3, a vertical longitudinal section of a furnace provided with my hot-air-feeding pipes situated both on top of the bridge-wall and over the door; Fig. 4, a detail plan view showing the manner of using the angle-pipe with the air-feeding pipe on 20 the bridge-wall when the air is to be taken from an opening at the rear of the wall; Fig. 5, a detail plan view showing the manner of arranging and using the pipe and angle-pipe when the boilers are set in batteries; Fig. 6, 25 a detail vertical sectional view showing the same; Fig. 7, a detail view of the air-receiving end of the pipe; Fig. 8, a detail view in end elevation of one of the pipe-sections; Fig. 9, a detail view of one of the angle-pipes.

30 Letters of like name and kind refer to like parts in each of the figures.

The object of my invention is to provide an improvement in the means for feeding hot air to furnaces; and to this end it consists in the 35 pipes made of the material and constructed, arranged, and operating substantially as hereinafter specified.

In the drawings, A designates the bridge-wall of a furnace of the ordinary form and 40 construction. The upper and forward edge of the wall is formed of a perforated pipe, B B, set into the wall and preferably projecting somewhat forward beyond its front face. This pipe, as shown, is preferably made with 45 its upper and lower sides, B' and B'', flat and parallel, and its rear side perpendicular, so that it can be set firmly and securely into the edge of the brick or masonry wall. The front side, B'', of the pipe is rounded and provided 50 with a number of small holes, b b, extending through to the internal bore, C, of the pipe.

One end of the pipe at one side of the bridge-wall is stopped with a plug, D, or other means. The other end is carried through the side wall of the furnace, so that its bore there commu- 55 nicates with the atmosphere. This end of the bore is preferably made funnel-shaped, so as to act best in connection with an injector-jet to be used to force air into and through the pipe. Said pipe I prefer to make not in one piece 60 but in a number of sections, each one of which is provided on one end with an annular recess or rabbet, E, around the pipe-bore, and on the other with an annular lip or projection, F, adapted to fit the annular rabbet or recess in 65 the end of the next section. A continuous pipe will thus be formed when the sections are put together.

As shown in the drawings, the bore of the pipe is made concentric with the curve of the 70 rounded side of the pipe. Through the rectangular portion of the pipe, on the other side of the bore, I contemplate making several small holes, G G, passing longitudinally through the pipe-sections.

If desired to hold the sections firmly together and brace the pipe, iron rods H H can be passed through these openings. Such rods are, however, not always necessary, and can be dispensed with without departing from my 80 invention.

My pipe-sections I make of a mixture of graphite and clay, the usual crucible mixture, the graphite being in excess of the clay.

When it is desired to take the air from an 85 opening in the rear of the bridge-wall, I use the angle-pipe I, (shown best in Fig. 9,) and connect one of its ends with the end of the next section of pipe by bringing them together so that the annular rib or projection 90 around the bore on the section end fits the rabbet or recess I' in the end of the angle-pipe. The other end of the angle-pipe is then turned to the rear and communicates with the opening K in the side wall of the furnace in rear 95 of the bridge-wall.

Where the boilers are set in batteries the angle-pipe connecting with the main pipe end section can be turned upward, as shown in Fig. 5, to take air from a passage, L, cut or 100 made down between the adjacent walls L' L'.

Instead of forming or cutting an air-passage

downward, as just described, the angle-piece may be turned downward and the air be taken into it from below the grate, out of the ash-pit, or from an air-passage extending up between 5 the adjoining walls of masonry.

Instead of placing the pipe in the upper front edge of the bridge-wall, it can be placed directly on top of the wall with its rounded and perforated side upward, as shown in Fig. 10 3, or over the door with its rounded and perforated side turned toward the rear end of the furnace.

Where the draft is weak I contemplate using both a pipe over the door and one on top of 15 the bridge-wall, each pipe being supplied with air forced into it as desired.

The shape of the pipe I prefer shall be as shown in the drawings, as being the most convenient when the pipe is to be placed on or 20 set into walls of fire-brick or masonry. I do not, however, intend herein to limit myself to any particular shape or configuration of it.

The size and dimensions of the pipe and bore thereof which I have found by actual use 25 to be advantageous are as follows: From the rounded side to the rear flat side I make six inches, while the distance between the flat parallel sides or faces is about five inches. The holes for the brace-rods I make about one- 30 half inch in diameter. The diameter of the bore of the pipe is about three inches, while the thickness of the lip, flange, or rib, and the width of the corresponding recess on the ends of the pipe-section is about one-half an inch 35 all around the bore. These relative dimensions are not essential, but can of course be changed as desired to suit any particular case. With the bore of the pipe three inches in diameter and the pipe five inches from one par- 40 allel side to the other, if, as described, the bore be made concentric with the rounded side of the pipe, the thickness of the material between the bore and pipe front will be one inch. The perforations bored through the front of the 45 pipe will then be not mere holes but passages of an inch in length. This is essential in order that the air shall be thoroughly heated as it passes out from the pipe.

The diameter of each of the air-discharging 50 passages is preferably about one-quarter of an inch.

Where, as heretofore, perforated metal pipes have been used, the walls of the pipe were so thin that there was no opportunity for the 55 jets of air to become heated to any consider- able extent by contact with the sides of the openings or perforations. The volume of air contained within the main-pipe bore could not become thoroughly heated, because while mov- 60 ing through the pipe only a portion of it could come into direct contact with the sides thereof and be heated directly therefrom. The result, then, of the use of metal pipes as heretofore has been that the air was not and could not be heated to the desirable degree while passing 65 through the pipe and its perforations in the desired quantity. Metal pipes have, more-

over, when thus used, been found to burn out rapidly.

It has been attempted heretofore to extend 70 the passages through which the air issues from the feed-pipe by using small tubes or nozzles in connection with the perforations in the pipe; but these have been found to burn off very quickly and become useless. The material 75 which I use—the ordinary crucible mixture—as is well known, cannot be burned out and destroyed like metal pipes.

I have found also, by actual experiment, 80 that this material is better than any heretofore used for hot-air-feeding pipes, because such material has the property of parting with its heat most rapidly, so that where the air-feeding pipe is made of it and used as described the heat of the fire of the furnace and 85 of the gases arising therefrom is transmitted most quickly and fully to the air within and passing through the pipe. If the air were allowed simply to flow through a pipe made of this material exposed to the heat of the fur- 90 nace, it would be heated very rapidly and to a high degree; but where, as in my pipe, the air within the pipe is allowed to flow out in fine jets through small passages of consider- 95 able length through the thick wall of the pipe, so that every portion of the air fed is brought into direct contact with a considerable amount of heat-imparting surface, the result is that 100 the air as delivered is heated so highly as to instantly form a combination with the hot 105 gases arising from the coal in excess. Such gases are then completely consumed, and a smokeless fire, with great saving of fuel, is secured.

To feed or force the air into the open end of 110 the pipe I contemplate using any air-forcing device or mechanism, but prefer a steam-jet to inject the air. I have not shown or described any form thereof herein, but intend to show and describe it in an application for patent for 115 the jet, to be filed shortly by me.

The advantageous action of the pipe made of crucible mixture, as described, is due to the presence of the graphite, which possesses to a great degree the quality of parting most 115 rapidly and freely with any heat imparted to it.

Instead of the clay mixed with the graphite I contemplate using any other suitable coher- 120 ing or binding material to bind and hold the particles of graphite together so as to form therewith a solid cohering mass.

Instead of clay I contemplate mixing with the graphite to form material for my pipes as- 125 bestus, cement, fire-clay, plaster-of-paris, and sand. Any one of these can be used with the graphite, or two or more, or all of them can be combined and mingled with it, as desired. In such mixtures, however, it is designed that the graphite shall form a large, preferably the largest, portion.

I am aware that a furnace has been provided with a fire-proof lining of plumbago, and that crucibles have been made of materials contain- 130 ing or in part composed of graphite or plumb-

bago. I am also aware that perforated air-feeding pipes have been arranged on the top and on the forward edge of the top of the bridge-wall of a furnace as well as over the door. I 5 do not therefore claim, broadly, such pipes so arranged.

Having thus described my invention, what I claim is—

1. An air heating and feeding pipe for furnaces, made of material containing graphite and provided with a series of perforations through its wall to allow the escape of the air from within the pipe into the furnace, substantially as and for the purpose described.

15 2. An air heating and feeding pipe for furnaces, made of graphite and clay, and provided with a series of perforations through its wall to allow the escape of the air within the pipe into the furnace, substantially as and for the 20 purpose described.

25 3. In an air heating and feeding apparatus, the pipe made of a mixture of graphite and clay placed within the furnace, provided with a series of small air-discharging openings and adapted to receive air from the outside of the furnace, substantially as shown and described.

30 4. The air heating and feeding apparatus for furnaces, consisting of the perforated pipe made of clay and graphite placed upon the bridge-wall and adapted to receive air from

outside the furnace, substantially as and for the purpose described.

5. The perforated pipe for air heaters and feeders for furnaces, composed of clay and graphite made in sections, each formed on one end with an annular lip around its bore and on the other with a corresponding annular recess, so that when the sections are put together one continuous pipe will be formed, substantially as and for the purpose described. 40

6. The pipe for air heaters and feeders for furnaces, composed of graphite and clay and made in sections, each one of which is provided on one end with an annular lip and on the other with a corresponding recess, so that when the sections are put together one continuous pipe will be formed, and with longitudinal openings or passages outside of the main boxes of the sections through which metal rods can be passed throughout the length of 50 the pipe to strengthen the pipe or hold the sections together, substantially as and for the purpose described.

In testimony that I claim the foregoing I have hereunto set my hand this 11th day of 55 October, A. D. 1884.
